US00D658511S

(12) **United States Design Patent**
Wai Kei

(10) **Patent No.:** **US D658,511 S**
(45) **Date of Patent:** **** May 1, 2012**

(54) **WRIST WATCH**

(75) Inventor: **Wong Wai Kei**, Siu Sai Wan Est (HK)

(73) Assignees: **Citizen Holdings Co., Ltd.**,
Nishitokyo-shi, Tokyo (JP); **Citizen
Watch Co., Ltd.**, Nishitokyo-shi, Tokyo
(JP)

(**) Term: **14 Years**

(21) Appl. No.: **29/408,820**

(22) Filed: **Dec. 16, 2011**

(51) LOC (9) Cl. **10-02**

(52) U.S. Cl. **D10/32**

(58) Field of Classification Search D10/30-39,
D10/122-132; 368/276, 281, 282, 80, 223,
368/228, 232; D11/3

See application file for complete search history.
